ELECTRIC CONDENSER

Filed Feb. 18, 1925

Inventor:
Chester W. Rice,
by *Alvanis E. Hunt*
His Attorney.

UNITED STATES PATENT OFFICE.

CHESTER W. RICE, OF SCHENECTADY, NEW YORK, ASSIGNOR TO GENERAL ELECTRIC COMPANY, A CORPORATION OF NEW YORK.

ELECTRIC CONDENSER.

Application filed February 18, 1925. Serial No. 10,112.

My invention relates to electric condensers, such for example as may be employed between sections of an antenna of the kind disclosed in my copending applications, Ser. No. 752,237 and No. 752,238, filed Nov. 25, 1924 for directive radio transmitting systems, assigned to the same assignee as the present application.

An object of my invention is to provide an improved condenser which may be inserted in an antenna to add capacitance thereto and which shall also function as a strain insulator between the adjacent sections of the antenna.

My invention will be better understood from the following description taken in connection with the accompanying drawing, and its scope will be pointed out in the appended claims.

In the single figure of the drawing, I have shown two sections 1 and 2 of an antenna conductor suspended as usual above ground and secured to opposite ends of the rod or shaft 3 of insulating material. An example of an insulating material which is well adapted for this purpose is a material formed of mica, glass and a binder and known as "mica-lex", but any suitable insulating rod may be used. Slidably mounted on the rod 3 are two similar sheet metal disks 4 each having its periphery turned back to form a stiffening flange 5 and to present a rounded edge facing the opposite disk in order to prevent a concentration of electrostatic flux, thereby avoiding destructive corona formation at this point. Each disk has its central supporting portion expanded or bulged in the form of a truncated cone 6, which portion fits over and is preferably united, as for example by soldering, to one end of a metal sleeve 7 which in turn fits over the insulating rod 3. By suitable means shown as a set screw 8, each sleeve and disk may be secured in any desired position on the rod 3, the disks being thus held spaced apart the proper distance to give the desired capacitance. Jumpers 9 connect the sleeves 7 with the adjacent sections of the antenna. As shown, each jumper has one end under the head of a screw 10 and has the other and twisted around the antenna conductor. The antenna conductor sections being secured to the rod 3, the tension of the antenna is taken

entirely by the insulating rod. By reason of the conical formation of the central portion of the disks 4, a maximum length of rod 3 is interposed between the two sleeves 7 which are in electrical connection with the antenna conductor. By this construction, the potential gradient along the rod is greatly reduced with a consequent reduction in the dielectric losses and tendency to arc over. Relative adjustment of the disks for tuning purposes is easily made by shifting one or both disks on the rod without mechanical interference with the antenna. When the desired relative position of the disks is found wherein the inductance of the antenna is substantially neutralized, the disks may be clamped to the rod and maintained in that position. As so arranged the mutual capacitance of the two disks because of their close proximity is far greater than their capacitance to ground.

What I claim as new and desire to secure by Letters Patent of the United States is:—

1. A combined condenser and strain insulator comprising a rod of insulating material adapted to be secured to adjacent sections of a conductor, a pair of opposed disks mounted on the rod, said disks having their central portions extending outwardly in opposite directions, and means for securing the disks to the rod at any suitable point along the rod whereby the disks may be adjusted with respect to each other.

2. A combined condenser and strain insulator comprising a rod of insulating material adapted to have its opposite ends secured to sections of an antenna conductor, a pair of opposed disks on said rod, a sleeve secured centrally of each disk and slidably mounted on the rod, and means for securing the sleeves to the rod.

3. A condenser comprising an insulating shaft and condenser plates mounted thereon in inductive relation to each other, one of said plates being adjustable on said shaft with respect to the other plate whereby the capacity of the condenser may be adjusted, and means for securing either of said plates in any suitable position along the shaft whereby the plates may be adjusted with respect to each other along the shaft and secured in the adjusted position.

4. A condenser comprising an insulating support and conducting plates thereon, said plates being provided with openings through which the insulator extends, the region of each plate about the opening being bulged for affecting the electrostatic flux about the support.
5. A condenser comprising an insulating support, and conducting plates thereon, said

plates being provided with openings through which the insulator extends, the border of each plate being formed so as to stiffen the plate and to affect the electrostatic flux along the border of the plates.

In witness whereof, I have hereunto set my ¹⁵ hand this 17th day of February, 1925.

CHESTER W. RICE.
